DIFFERENTIAL ACTUATING MECHANISM

Alva G. Russell, Stamford, Conn., assignor to Pitney-Bowes, Inc., Stamford, Conn., a corporation of Delaware

Application April 1, 1948, Serial No. 18,438

4 Claims. (Cl. 235—81)

1

This invention relates to actuator mechanism for use in effecting the accumulation of settable values in register numeral wheels.

It is one object of the invention to effect the accumulation of settable values in register wheels by means of actuator mechanism, wherein the controlling element includes a combined peripheral toothed and non-toothed portion and wherein the non-toothed portion directly controls the actuation of the register wheels during a cycle of operation.

It is another object to provide an actuator element including settable means to vary the toothed and non-toothed portions of the actuator element and means whereby the non-toothed portion will control the actuation of an accumulator during a cycle of operation.

It is another object to provide register actuator mechanism, wherein a transmission element, which is geared to a register numeral wheel, is adapted to be rotated when a pinion, meshing therewith and moved therearound becomes choked but continues to move in a circumferential direction while choked.

With the above and other objects in view, which will appear as the description proceeds, the invention resides in the combination and arrangement of parts and in the details of construction hereinafter described and claimed, it being understood that various changes in the precise embodiment of the invention herein disclosed may be made within the scope of what is claimed without departing from the spirit of the invention.

A preferred embodiment of the invention is illustrated in the accompanying drawings, wherein;

Fig. 1 is a plan view of a two unit accumulator and actuator device;

Fig. 2 is a front elevational view of Fig. 1 with the front wall broken away and with parts shown in section;

Fig. 3 is a vertical sectional view taken along the line 3—3 of Fig. 2, through one unit of the actuator and transmission mechanism;

Fig. 4 is an enlarged detail sectional view taken along the line 4—4 of Fig. 2;

Fig. 5 is an enlarged perspective view of the actuator and transmission gears and showing their associated pinions moving circumferentially around the teeth of the actuator and transmission gears during a cycle of operation without effecting rotation of the transmission gear;

Fig. 6 is a fragmentary perspective view similar to Fig. 5 and showing one pinion in a choked position relative to the peripheral sur-

2

face of the short actuator gear teeth during the latter part of the cycle of operation, and the consequent drive of the transmission gear; and

Fig. 7 is a fragmentary front view of the actuator gears and pinion arranged in "0" position.

Two units of an accumulator and actuator mechanism are shown within a supporting frame structure 10. The accumulator mechanism comprises numeral wheels 11 rotatively supported upon a shaft 12, which shaft is carried by the front and rear walls 13—13 of the frame 10. The numeral wheels 11 are preferably of the internal differential drive type, such as disclosed in patent application Serial No. 760,590, which permit the individual drive thereof, transfer being effected by means of a Geneva pinion 14 from a numeral wheel of a lower to a higher order.

20 Actuator means is provided to effect rotation of the numeral wheels 11 in accordance with a pre-selected value. Each actuator comprises two actuator gears which have an equal number of normal length and shorter length teeth therearound, and wherein the shorter length teeth are identical to the normal length teeth but have their top portions cut back to form a peripheral surface at substantially the pitch diameter of the normal teeth. Also, one of the shorter length teeth of each gear is half of a tooth greater in width than the other shorter length teeth.

One unit of the actuator and transmission mechanism will now be described. As best shown in Fig. 5, an actuator gear structure comprises 35 two adjacent gears 15 and 16, each having identical long teeth 17 and short teeth 18, but reversely arranged. When in a "0" position, the wider teeth, indicated at 18a, are aligned and the short teeth 18 of one gear are aligned with the long teeth 17 of the other gear, as indicated in Fig. 7.

The actuator gear 15 is supported on a shaft 19 but is arranged in a stationary position, such as indicated by the pin 21, Fig. 3, which is secured within a hub 22 of the gear 15 and the front wall 13. The second actuator gear 16 is adapted to be rotatively adjusted about the hub 22 of the actuator gear 15 by means of a setting lever 23. Said setting lever 23 has a head portion 23a which is connected with a hub 24 of the rotative actuator gear 16, as best shown in Fig. 3.

A disc 25 is fixed to the shaft 19 and is adapted to rotatively support a pinion structure 26. Said pinion structure 26 comprises two separate pinions 26a—26b, joined by a central integral shaft portion 30, which shaft portion is mounted

within a bearing 30a in any suitable manner. Although the pinion structure comprises two separate pinions, to provide for convenience of mounting, it is essentially the equivalent of a single pinion element. The pinion 26a extends beyond one face of the disc 25 and meshes with the combined actuator gears 15-16. The pinion 26b extends beyond the other face of the disc 25 and meshes with a transmission gear 27.

The transmission gear 27 has twenty teeth and is rotatively mounted on the shaft 19. Said transmission gear 27 also has a hub portion 28 upon which another gear 29 is fixed, and said gear 29 meshes with a gear 31 secured to the numeral wheel 11.

When the rotative actuator gear 16 is adjusted to a selected value, the short toothed peripheral surface will be increased one full tooth for each digit value selected. With the wider teeth 18a in alignment in the "0" position, and the teeth adjustable in full tooth increments, each short tooth, which has advanced beyond the wider tooth of the stationary gear 15, will overlap the tooth space between companion short teeth of the stationary gear, as clearly indicated in Figs. 5 and 6. As shown, in Fig. 5, for example, the selected value "5" places five of the shorter teeth on each of the actuator gears 15 and 16 in an overlapping order, and their peripheral surfaces are in continuous alignment. In other words, five short teeth of one gear are positioned opposite the tooth spaces of five short teeth of the other gear and their individual peripheral surfaces form one continuously aligned surface over which the pinion 26a is adapted to slide while choked. Also, simultaneously with the increase of the non-toothed surface, the toothed surface is decreased a like amount.

A cyclical drive is provided for the shaft 19 to effect rotation of the disc 25 and the consequent movement of the pinions 26a-26b in a circumferential path around the toothed and non-toothed surfaces of the actuator gears 15 and 16. The pinion 26b meshes with a transmission gear 27 and, since said pinion forms an integral part with the pinion 26a, it will rotate around the teeth of the transmission gear when pinion 26a is rotated while moving around the teeth of the actuator gears 15 and 16. When however, the pinion 26a passes from the normal long toothed portion to the continuously aligned peripheral surface of the short toothed portion of said actuator gears 15-16, the pinion 26a will become choked, as shown in Fig. 6, and will thus slide non-rotatively in the direction of the arrow, across the peripheral surface thereof. The pinion 26b will not rotate while the pinion 26a is choked, but due to the continued movement of the pinions about the axis of the shaft 19, the transmission gear 29 will be rotated, and, through gear 31, will effect rotation of the numeral wheel 11 in accordance with the value set.

A detent rocker arm 32 is mounted on a pin 33 and has a detent portion 34 urged between teeth 35 of a sector 36, formed as a part of the setting lever head portion 23a. A notch 37 is provided in the disc 25, opposite a wing portion 38 of the detent arm 32, to thereby permit adjustment of the setting lever 23 and actuator gear 16, when the mechanism is in a home position. However, when a cycle of operation is effected, the peripheral surface of the disc 25 will move into the path of the wing portion 38 of the detent arm 34 to effect locking of said

arm and thus prevent adjustment of the setting lever during a cycle of operation.

Having described the invention what is claimed is:

5. In register actuating mechanism, an accumulator member, a transmission gear having a geared driving connection with the accumulator member, a composite actuator gear structure having an adjustable toothed and an adjustable non-toothed peripheral surface, a pinion having teeth in operative relation with the transmission and composite actuator gear structure, and a cyclically driven support for said pinion to effect movement of said pinion circumferentially around the composite actuator gear structure and transmission gear, said pinion being rotatable while engaging the teeth of the composite actuator gear structure and non-rotatable while two successive teeth thereof engage and move over the non-toothed peripheral surface of said composite actuator gear structure during each cycle of movement of the pinion support, whereby the transmission gear and accumulator member are adapted to be driven while the pinion teeth move non-rotatively over the non-toothed surface of the composite actuator gear structure.

2. In register actuating mechanism, an accumulator member, a transmission gear having a geared driving connection with the accumulator member, an actuator comprising two similar and adjacently positioned gears arranged on a common axis with the transmission gear, teeth on said similar gears jointly arranged to provide a toothed and non-toothed peripheral surface, one of said similar gears being rotatively adjustable to effect a simultaneous increase of the combined non-toothed peripheral surface and an equivalent decrease of the combined toothed peripheral surfaces of the similar gears, a pinion having teeth in operative relation with the actuator and transmission gears, and a cyclical drive for moving the pinion circumferentially around the actuator and transmission gears, said pinion being rotatable while engaging the teeth of the combined actuator gears and non-rotatable while two successive teeth thereof engage and move over the non-toothed peripheral surface of said combined actuator gears during each cycle of movement of said pinion, whereby the transmission gear and accumulator member are adapted to be driven while the pinion moves non-rotatively over the non-toothed surface of the combined gears.

3. In register actuating mechanism, an accumulator member, a transmission gear having a geared driving connection with the accumulator member, an actuator member comprising two similar gears each having successive normal and short length teeth and further having a common axis with the transmission gear, one of the short length teeth of each similar gear being greater in width than the other teeth, said similar gears being adjacently positioned and faced in a reverse order with the two wider teeth aligned in "0" position, one of said similar gears being rotatively adjustable relative to the other to produce an increasing continuous short toothed peripheral surface of the combined similar gears upon each step of adjustment in one direction, a pinion having teeth in operative relation with the said similar and transmission gears, and a cyclically driven support for said pinion to effect movement of said pinion circumferentially around the similar and transmission gears, said pinion being

rotatable while engaging the teeth of the combined similar gears and non-rotatable while two successive teeth thereof engage and move over the continuous short toothed surface of said similar gears during each cycle of movement of said pinion, whereby the transmission gear and accumulator member are adapted to be driven while the pinion moves non-rotatively over the non-toothed surface of the similar gears.

4. In register actuating mechanism, an accumulator member, actuator means including a transmission gear having a geared driving connection with the accumulator member, an actuator member comprising two similar gears having a common axis with the transmission gear, each similar gear also having a number of normal length teeth and an equal number of shorter teeth, said shorter teeth having a peripheral surface corresponding with substantially the pitch circle line of the normal length teeth, one of the shorter teeth of each similar gear being greater in width than the other teeth, said similar gears being adjacently positioned and faced in a reverse order with the two wider teeth aligned in "0" position, one of said similar gears being rotatively adjustable relative to the other in one tooth increments to effect spacing of the short teeth of one gear opposite the tooth spaces of the other gear and to produce an increasing continuous short toothed peripheral surface of the combined similar gears upon each step of adjustment in one direction, a pinion having teeth in operative relation with the similar and transmission gears, and a cyclically driven support for said pinion to effect movement of said

pinion circumferentially around the similar and transmission gears, said pinion being rotatable while engaging the teeth of the combined similar gears and non-rotatable while two successive teeth thereof engage and move over the continuous short toothed surface of said similar gears during each cycle of movement of said pinion, whereby the transmission gear and accumulator member are adapted to be driven while the pinion moves non-rotatively over the non-toothed surface of the gear.
